CLAIM

The ornamental design for a slanted diagonal sorter, as shown and described.

DESCRIPTION

FIG. 1 is a front elevational view of a slanted diagonal sorter showing my new design, the rear elevational view being identical;

FIG. 2 is a top plan view;

FIG. 3 is a bottom plan view;

FIG. 4 is a left side elevational view; and

FIG. 5 is a right side elevational view thereof.

FIG. 1.

FIG. 2

FIG. 3.

FIG. 4.

FIG. 5.
